COMBINED SIPHON AND CIRCULATOR FOR
STEAM BOILERS

Frank Le Blanc, St. Albans, Vt.

Application August 13, 1941, Serial No. 406,717

4 Claims. (Cl. 122—68)

This invention relates to improvements in siphons and circulators for steam boilers and especially adaptable for steam locomotive boilers, and has for the primary object the provision of a device of this character which besides providing an efficient circulation of boiler water through the firebox and over the crown sheet of said firebox will eliminate burning out or cracking of walls or portions of the siphon due to incomplete circulation of water throughout the entire siphon.

With these and other objects in view as will become more apparent as the description proceeds, the invention consists in certain novel features of construction, combination and arrangement of parts which will be hereinafter more fully described and claimed.

For a complete understanding of my invention, reference is to be had to the following description and accompanying drawings, in which

Figure 1 is a top plan view of my combined siphon and circulator adapted for use in a steam locomotive boiler.

Figure 2 is a sectional view taken on a line 2—2 of Figure 1.

Figure 3 is a vertical sectional view taken on the line 3—3 of Figure 2.

Figure 4 is a fragmentary vertical sectional view taken on a line 4—4 of Figure 2.

Figure 5 is a fragmentary enlarged sectional view illustrating the connection for the circulator with the siphon and taken on a line 5—5 of Figure 2, and

Figure 6 is a transverse sectional view through the elongated deflector in the siphon.

Referring in detail to the drawings, the numeral 5 designates a siphon generally especially adapted for providing efficient circulation of water through a firebox of a steam locomotive boiler and to distribute water over the crown sheet of the firebox of the boiler by a thermo-siphon action. Two or more of the siphons are employed in a boiler and extend from the throat sheet 6 of the boiler to the crown sheet 7 within the firebox. The crown sheet is provided with a slot 8 through which the water from the siphon is discharged over said crown sheet.

The siphon 5 includes a portion 9 of a narrow elongated formation and a tubular portion 10 connected to the flange 6' of the throat sheet 6 by welding or some other suitable means. The portion 9 consists of substantially spaced parallel sides 10' connected in spaced relation by hollow stay bolts 11. The portion 9 also includes end walls 12 and 12'. The walls of the portion 55

merge into the tubular portion 10. The end wall 12 is of a greater height than the end wall 12' and the side walls shaped to match the differences in the height of the end walls with the upper edges of the walls terminating in the same plane and butt welded to the crown sheet 7. This formation of the side and end walls of the portion 9 and the formation thereof onto the tubular portion 10 disposes the latter in an upwardly inclined plane, as shown in Figure 2.

By a thermo-siphon action the water flows through the siphon in the direction indicated by the arrows, first entering the tubular portion 10 from the boiler by way of an opening provided in the throat sheet. This water passes upwardly through the portion 9 and discharges over the crown sheet. The tendency of the water circulating through the siphon after leaving the tubular portion 10 is to rise more rapidly through the forward end of the portion 9 than the rear end. Consequently there is always a possibility of the water boiling out at the rear lower end of the siphon and subject the portion A to cracking or deterioration owing to the excessive amount of heat thereon and the lack of circulation of water. To prevent this faulty circulation of water and to assure a substantially uniform circulation of water throughout the portion 9 an elongated deflector plate 13 is provided which is located in the lower part of the portion 9 where the side and end walls merge into the tubular portion 10 forming a passage 10' along the bottom of the portion 9 of the siphon. The lower end of the deflector is spaced from the walls of the tubular portion 10 so as to divide the incoming water causing a portion thereof to follow along the passage 10' and then upwardly in the rear part of the portion 9 while the other portion of water flows over the lower end of the deflector and thence upwardly through the forward part of the portion 9 of the siphon and thereby assure a complete circulation of water throughout the entire area of the portion 9 of the siphon eliminating any possibility of the walls cracking or deteriorating.

The deflector 13 is transversely curved and has formed thereon pairs of spaced apertured ears 14 through which certain of the lowermost stay bolts 11 extend for supporting the deflector in place within the siphon and as shown in Figure 6.

Outturned flanges 15 are formed integrally with the side and end walls of the portion 9 at the upper edges of said walls and are butt welded onto the crown sheet and also secured thereto by stay bolts 16 employed in the support of the

crown sheet. The flanges of the end walls where meeting are welded together, as shown at 17.

A water circulator is provided for the side sheets 18 and door sheet 19 of the boiler, the circulators at the two sides of the boiler being of identical construction, and comprise a vertical tube 20 positioned at the junction of the side sheet with the door sheet and from which a horizontal tube 21 extends forwardly in the side sheet. The tube 21 is connected at its front end to a pair of intermediate vertical tubes 22 and a front vertical tube 23, all connected by vertically spaced horizontal tubes 24. Each of the vertical tubes are perforated as shown at 25 and the horizontal tubes are offset as shown in Figure 2.

A tube 26 also extends laterally upwardly and rearwardly from the front vertical tube 23 to the front end wall 12.

A combustion chamber circulation system is also provided for the combustion chamber C, and comprises a pan 27 having flanges 28 around its edges which are butt welded to the edges of an opening 29 in the crown sheet 7 at the top of the combustion chamber and also supported by long stay bolts 30. Circulating tubes 31 lead from the front vertical tube 23 to the sides of the pan and circulating tubes 32 also lead from the sides of the pan to pockets 33 formed on the inner surfaces of the combustion chamber forwardly of the front vertical tubes 23.

The front vertical tubes 23 are positioned in the side sheets at the junction thereof with the throat sheet 6.

The throat sheet 6 is provided with a clean-out plug 34 and the door sheet is also provided with a clean-out plug 35 in alignment with the tubular portion 10 of the siphon.

Having thus described my invention, what I claim is:

1. A combined siphon and water circulation system for steam boilers of a type including a crown sheet, a throat sheet, a door sheet and side sheets, said system comprising a siphon device having communication with the throat sheet and

crown sheet of the boiler and a circulation device positioned within the side sheets and connected to the siphon device, said siphon and circulation devices being adapted to receive and convey fluid from the throat sheet, the door sheet and the side sheets to the crown sheet.

2. A combined siphon and water circulation system for steam boilers of a type including a crown sheet, a throat sheet, a door sheet and side sheets, said system comprising a siphon device having communication with the throat sheet and crown sheet of the boiler and a circulation device positioned within the side sheets and connected to the siphon device, said circulation device being adapted to receive and convey fluid from the door sheet and side sheets to the siphon and said siphon being adapted to convey fluid from the throat sheet to the crown sheet.

3. A combined siphon and water circulation system for steam boilers of a type including a crown sheet, a throat sheet, a door sheet and side sheets, said system comprising a siphon device having communication with the throat sheet and crown sheet of the boiler and a circulation device positioned in the side sheets and connected to the siphon device, said circulation device comprising interconnected vertical and horizontal perforated tubes, including a tube at the junction of the door sheet with the side sheets, and said siphon and circulation devices cooperating to convey fluid to the crown sheet from said remaining sheets.

4. A circulation system for steam boilers of a type including a combustion chamber having a crown sheet and side sheets, perforated tubes in the side sheets, a siphon device having communication with the crown sheet, tubes connecting the perforated tubes with the siphon device, pockets in the walls of the crown sheet and side sheets, tubes connecting the pockets to each other, and tubes connecting the pocket in the crown sheet to the tubes in side sheets.

FRANK LE BLANC.
